LOUIS V. ARONSON, OF NEWARK, NEW JERSEY.

DESIGN FOR A CLOCK-CASE.

SPECIFICATION forming part of Design No. 35,798, dated March 11, 1902.

Application filed February 11, 1902. Serial No. 93,632. Term of patent 3½ years.

To all whom it may concern:

Be it known that I, LOUIS V. ARONSON, a citizen of the United States, residing at Newark, in the county of Essex and State of New Jersey, have invented and produced a new and original Design for a Clock-Case, of which the following is a specification, reference being had to the accompanying drawings, forming part thereof.

As shown in the accompanying drawings, the leading or material features of my design are the ornamental base with scroll feet, the fluted column, the female figure, the second column, and the spray of foliage surmounting the socket for the clock.

A second column d, extending upward from the base behind and a little to the right of the figure, terminates in a socket e for the clock, the casing of the socket being encircled with foliage and having the foliage extended around the socket and terminated in a scroll above the top of the same, the female figure standing upon the base with its back toward the socket and one elbow resting on the column. The female figure is draped quite loosely, and the whole design is in the empire style of the sixteenth century.

Having thus described my invention, what I claim is—

The design for a clock-case as herein shown and described.

Signed at Newark, in the county of Essex and State of New Jersey, this 3d day of February, 1902.

LOUIS V. ARONSON.
